UNITED STATES PATENT OFFICE.

ALPHEUS W. ALTORFER, OF ROANOKE, ILLINOIS, ASSIGNOR TO POWER WASHING MACHINE CO., OF PEORIA, ILLINOIS, A CORPORATION OF ILLINOIS.

DRIVING MECHANISM.

1,251,854.

Specification of Letters Patent. Patented Jan. 1, 1918.

Application filed February 24, 1913. Serial No. 750,295.

To all whom it may concern:

Be it known that I, ALPHEUS W. ALTORFER, a citizen of the United States, residing at Roanoke, in the county of Woodford and State of Illinois, have invented certain new and useful Improvements in Driving Mechanisms, of which the following is a specification.

This invention has reference to a new and improved driving mechanism.

One of the objects of the present invention is to provide a driving mechanism for a wringer, which embodies the features of a drive for moving the wringer bodily from one position to another, on its support, and for actuating the wringer mechanism, when said mechanism is in adjusted positions and held stationary, on its support.

This invention has for a further object to provide an operating mechanism for a wringer, and particularly to that type of wringer employed in connection with "power washing machines," wherein the wringer is not only power operated but is movable on its support to position the wringer adjacent the washing machine, or adjacent a rinsing tub or other receptacle removed or spaced from said washing machine. In machines of the type mentioned, as far as I am aware, the wringer has been slidably supported and manually movable, or pivotally supported to be manually swung to and from the washing machine or rinsing tub or other receptacle or supported at the upper end of a vertically disposed shaft or standard and swingable in an arc of a circle about said shaft or standard. In the present invention I have shown the wringer supported and slidable on its support, but instead of being manually movable, by that I mean, the operator must push the wringer from one position to another, the driving mechanism is so arranged that when operated, if the wringer support is not held, the resulting operation of the driving mechanism is to move the wringer bodily from one position to another on its frame support, but any resistance placed on the wringer or its supporting member, such as will hold it against movement, will cause the driving mechanism to actuate the wringer proper. Included in the driving mechanism is a clutch mechanism for regulating such driving mechanism and for regulating same when desired.

In the drawings:—

Figure 1 is a side elevation of a machine embodying my invention;

Fig. 2 is a bottom plan view, partly in section, of the gearing and clutch for controlling the wringer driving mechanism;

Fig. 3 is a detail of the locking means for holding the wringer in adjusted positions, and

Fig. 4 is a detail of a modified form of wringer driving means.

6 refers generally to the frame of the machine, supported by suitable legs and braced in any suitable manner, and 7 denotes the bed or floor of the machine on which may be supported a washing machine 8, and a rinse tub 9 or other receptacle. The frame of the machine may be only long enough for a washing machine and a rinse tub, or it may be long enough to support two rinsing tubs and an additional receptacle, if desired.

10 denotes a wringer support and comprises standards 11, although only the one in the foreground is shown, and shoes or runners 12, only one of which is shown. Said shoes or runners are movable along the side frames of the machine, as shown. The wringer proper is designated 13, although not shown in detail, as the same may be of any of the well known or preferred types of wringers, except that the spindle 14 of one of the rollers should be long enough to carry the driving wheel 15. The runner 12 shown in the foreground, has the bearing plate 16 on which is journaled the wheels 17 and 18.

The driving shaft, designated 19, is journaled in bearings 20 secured to the underside of the bed or floor 7, and on one end carries a member 21 adapted to receive power from a suitable source such as a gasoline engine or other suitable motor and on the opposite end of said shaft is carried a gear wheel 22. The gear wheel 22 meshes in and is adapted to transmit motion to a gear wheel 23 on a clutch shaft 24. The shaft 24 is journaled in bearings 25 secured to the underside of the bed or floor 7. While it has not been shown, the gear wheel 23 may be the means of communicating power to the interior mechanism of the washing machine. On the clutch shaft 24 is loosely carried the bevel gear wheels 26 and 27, each meshing in a bevel gear wheel 28 carried on the counter shaft 29 and said shaft 29 is journaled in bearings 30 and 31. On the clutch shaft 24, 110

between the gear wheels 26 and 27 is slidably keyed a clutch member 32 and said clutch member 32 is adapted to have a clutch engaging relation with clutch faces 33 and 34, 5 on gear wheels 26 and 27, respectively, see Fig. 2. To shift the clutch member 32 on the shaft 24, I provide the rocking rod 35, its inner end engaging said clutch member 32 and its outer end passing through a bearing plate 36 with a hand hold 37 for rocking said rod 35 to move the clutch member into or out of engaging relation with said wheels 26 and 27, or for placing said clutch member in a neutral position, between said 10 gear wheels 26 and 27.

On the outer end of the counter shaft 29 is carried a sprocket wheel 38 adapted to drive a sprocket chain or belt 39. This sprocket chain or belt 39 passes around the 20 wheel 18, up and around the wheel 15 on the wringer spindle 14, down and around the wheel 17, to and around a wheel 40 journaled at the opposite end of the machine from the sprocket wheel 38, and to and around said 25 sprocket wheel 38, from which it receives its power.

In operation, when said clutch 32 is thrown into clutch engaging relation with one of said wheels 26 or 27 the chain or belt 30 39 will be operated in a direction to move said wringer bodily in a direction away from said washing machine, or in a direction toward said washing machine. The foregoing statement is based on the assumption 35 that the wringer support is free to be moved along the supporting frame. If the wringer has been moved in the direction of the washing machine, when its support comes into engagement with the washing 40 machine it will stop, but the chain or belt 39 will not stop, but on the contrary will start the wringer in operation. This is also true when the wringer support has been moved far enough to the left so as to cause 45 the wheel 17 to come into engagement with the wheel 40. Such engagement will stop the wringer in its movement and the chain or belt 39 will transmit motion to the wringer proper.

50 I prefer, however, to lock the wringer in its adjusted positions on the frame. This is desirable for two reasons, one being that, when the wringer and its support have been moved to a predetermined position at the 55 other end of the machine, the said support will be locked or held to allow the chain or belt 39 to transmit motion to the wringer rolls; the other reason for locking the wringer being, that the wringer proper 60 will not always be driven in the direction it has been moved on its support and it is desirable to reverse the movement of the wringer rolls. For instance, assuming that the chain or belt 39 is moving in the direction 65 of the sprocket wheel 38 and that the

support 10 is not held, it is obvious that the support and its wringer will be moved bodily toward the washing machine. As soon as the support 10 comes into contact with the washing machine and it is stopped, 70 the chain or belt 39 will operate the wringer 13 but in a reverse direction from that desired to wring clothes passed from the washing machine to the tub of rinse water, so it is necessary to reverse the gearing for 75 operating the belt 39, and when the belt has been reversed, if the support 10 is not held it will be moved bodily away from the washing machine, and to prevent this, I provide the spring held detent 41 carried by the shoe 80 or runner 41 which is adapted to enter the perforations 42 or 43 in the main frame or floor thereof, which will lock and hold the wringer support against movement and which will drop into place when the support 85 has been moved to position, whereby the drive for moving the wringer bodily, will be automatically transferred as a driving mechanism for moving the wringer bodily, to a drive for operating the wringer proper. 90

In Fig. 4 I show a modified form of driving device for moving the wringer support bodily and for operating the wringer proper. In this view the chain or belt 39 after it passes around the wheel 18 engages and 95 passes around a sprocket wheel 44 carried on a stub shaft 45 having a bearing on the shoe or runner 12. On the stub shaft 45 is a second wheel, not shown, which operates a belt 46 and said belt 46 in turn operates 100 the wheel 15 on the spindle 14 and one of the wringer rolls.

Employing a device such as I have shown and described, the operator may move the wringer bodily by power instead of by hand, 105 as heretofore, and by means of the clutch devices illustrated, or other equivalent means, the operator has complete control over the movement of the wringer support and the operation of the wringer proper. 110

I do not wish to be limited to the precise mechanical elements herein employed and described, as I am fully aware that modifications may be made, not only in the appearance of the machine, and the arrangements of its parts, but also as to the individual elements thereof, without departing from the spirit and scope of the invention. 115

What I claim is:—

1. In a device of the character described, 120 in combination, a frame, a wringer, a support for said wringer movable to two or more predetermined positions, in which positions said support will be stationary, a driving means, connections between said driving means and said support, adapted to move said support to said predetermined stationary positions, said connections arranged to operate said wringer when said support is in its predetermined stationary 125 130

positions, and means for reversing the direction of movement of said wringer as desired.

2. In a device of the character described, in combination, a frame, a wringer, a support for said wringer movable to two or more predetermined positions, in which positions said support will be stationary, means to lock said support in different positions, a driving means, connections between said driving means and said support, adapted to move said support to said predetermined stationary positions, said connections arranged to operate said wringer when said support is in its predetermined stationary positions, and means for reversing the direction of movement of said wringer, as desired.

3. In a device of the character described, in combination, a frame, a wringer, a support for said wringer movable to two or more predetermined positions on said frame, a driving means, connections between said driving means and said support, said connections adapted to transfer the support to its different positions, and adapted to operate said wringer when said support is stationary in its different positions, and means to reverse the movement of said connections, as desired, so as to reverse the movement of the support and to change the direction of rotation of said wringer.

4. In a device of the character described, in combination, a frame, a wringer, a support for said wringer movable to two or more predetermined positions on said frame, a driving means, connections between said driving means and said support, said connections adapted to transfer the support to its different positions, and adapted to operate said wringer when said support is stationary in its different positions, means to lock the support in its different positions, and means to reverse the movement of said connections,

as desired, so as to reverse the movement of the support and to change the direction of rotation of said wringer.

5. In a device of the character described, in combination, a frame, a wringer, a support for said wringer movable to position the wringer in two or more different positions on said frame, a driving means, connections between said driving means and said support, said connections being so arranged that said support may be moved by said driving means, and said wringer driven thereby, and reversing means to change the direction of movement of said wringer, whereby the material to be treated by said wringer may be moved in different directions, as desired.

6. In a device of the character described, in combination, a frame forming a rest for a washing machine and one or more receptacles, a wringer, a support for said wringer movable to cause the wringer to register with the position of said washing machine or receptacles, a driving means, connections between said driving means and said support, said connections being arranged so that said support may be moved by said driving means to cause the wringer to register with the position of said washing machine or receptacles, and to operate said wringer when registering with the washing machine or receptacles, and means to reverse the direction of movement of the support, and to change the direction of movement of said wringer, as desired, during the period when said wringer is registered with the position of said washing machine or said receptacles.

In testimony whereof I affix my signature, in presence of two witnesses.

ALPHEUS W. ALTORFER.
